United States Patent Office.

EDWARD EDMONDS WARNER, JACOB WILLIAM WALTON, AND ROBERT VINE, OF PHILADELPHIA, PENNSYLVANIA.

Letters Patent No. 105,148, dated July 5, 1870.

IMPROVEMENT IN METAL-BACKED COMBS.

The Schedule referred to in these Letters Patent and making part of the same

We, EDWARD EDMONDS WARNER, JACOB WILLIAM WALTON, and ROBERT VINE, all of Philadelphia, county of Philadelphia, State of Pennsylvania, have invented an Improvement in Metal-backed Combs, of which the following is a specification.

Nature and Object of the Invention.

Our invention consists of a method of fastening metal backs to combs, by means of solder or cement, adapted to the interior of the projecting ends of the metal back, and to recesses or projections of the ends of the comb, as fully described hereafter, the object of our invention being to produce a strong metal-backed comb of neat appearance, and with none of the objections common to metal-backed combs fastened by the usual method.

Description of the Accompanying Drawing.

Figure 1 is a side view of our improved metal-backed comb;

Figure 2, an enlarged perspective view of a portion of the metal back and end of the comb, detached from each other;

Figure 3, the same, shewing the metal back adapted to the comb;

Figure 4, also a perspective view, showing the lower edges of the metal back bent around the end of the comb;

Figure 5, a sectional view of the fastening, complete;

Figure 6, a sectional plan of fig. 5; and

Figure 7, a sectional view of a modification.

General Description.

Metal backs are usually attached to combs by forming on each side of the latter a longitudinal groove, into which the metal composing the back is pinched.

This plan is objectionable for two reasons; first, on account of the labor of forming the grooves on both sides of and throughout the entire length of the comb; and, secondly, because these grooves so weaken the comb that it frequently becomes broken off beneath the metal back, notwithstanding the additional strength imparted by the latter.

Metal backs have also been riveted to combs, but backs thus attached are apt to become loose, rendering it difficult to keep the comb clean.

The object of our invention has been to overcome both of these objections, and to produce a metal-backed comb of neat appearance, and having a fastening of

sufficient strength to prevent breaking of the comb or loosening of the back.

On reference to the drawing—

A represents the comb, and

B, the sheet-metal back, which is bent over the comb as usual, so as to form the rounded upper edge a.

The lower edges of the metal back are pressed against the flat sides of the comb, as shown in fig. 3, and its opposite ends, which project a short distance beyond the ends of the comb, are bent inward at the lower corners c c, so as to partially embrace the comb, and thus prevent any longitudinal displacement of the back.

A notch or recess, h, is cut in each end of the comb, at a point close to its rear edge, and beneath the metal back B, and this notch, as well as the space x within the projecting portion of the back, beyond the end of the comb, is filled with a mass of solder or cement, i, which completes the fastening, and effectually prevents the back from becoming detached.

It will thus be seen that, by simply notching or recessing the ends of the comb, and filling the same, as well as a portion of the metal back, with solder or cement, a more effectual fastening can be obtained than by the objectionable rivets or longitudinal grooves cut in the comb.

The same result might also be obtained by having a projection at each end of the comb, or by inserting in the comb a pin, z, around which to cast the solder or cement, as shown in fig. 1. In this latter case, especially if solder were used, it would be preferable to employ a metal pin, as the comb and back would then be actually soldered together.

Claim.

A metal-backed comb, in which the metal back is secured to the comb by soft solder, or other soft metal or cement, within a space, x, of the back, and inclosing a projecting portion of, or extending into a recess in the comb, substantially as described.

In testimony whereof we have signed our names to this specification in the presence of two subscribing witnesses.

EDWARD EDMONDS WARNER.
JACOB WILLIAM WALTON.
ROBERT VINE.
